Attorneys

UNITED STATES PATENT OFFICE.

ANTHONY FRICKER, OF LAKWOOD, OHIO.

CLASP.

Application filed June 4, 1923. Serial No. 643,282.

This invention relates to clasps, such as are used for temporarily binding together thick masses of paper sheets, files or the like, up to thicknesses of an inch or so. The 5 present clasp is an improvement upon the clasp described and claimed in my prior patent for clasps, No. 1,493,072, granted May 6, 1926.

The object of the present invention is to 10 provide an improved clasp of the character described in which one or both of the clasp arms is so formed as to provide adjacent the arm contacting portions at the inner end of the clasp mouth a region where the arms do 15 not contact, thereby enabling paper sheets and the like, after passing through the clasp mouth and between the contacting portions at the inner end thereof, to be readily and easily moved or guided without undue re- 20 sistance to the inner contacting portions of the clasp arms. Buckling and shifting of the paper sheets or the like, while inserting them in the clasp, are therefore avoided, ma- 25 terially increasing the efficiency of the clasp.

Further objects of the invention are in part obvious and in part will appear more in detail hereinafter.

In the drawing, which represents one suitable embodiment of the invention, Fig. 1 is 30 a perspective view of my improved clasp; Fig. 2 is an edge view thereof; and Fig. 3 is a similar view with the clasp arms shown separated.

As illustrated in the drawing, the clasp is 35 made from a single strip of steel of any suitable width and length, one satisfactory size being about three quarters of an inch wide and approximately six inches long. The head, indicated generally at 1, is in the form 40 of a loop or eye joining the two arms 2, which lie substantially parallel and substantially in contact over an appreciable portion of their length, due to the formation of the clasp in a manner to impart inherent tension 45 thereto, such that the normal position of the arms, if they could pass each other, would be at approximately right angles to each other. This effect is secured in the present 50 clasp by forming the eye 1, with two side bends 3 and an end bend 4, said bends being put into the metal of the tempered strip so that subsequent tempering is unnecessary.

The side and end bends 3, 4 are formed in 55 a manner to overbend the material, or in other words, to put into the clasp more ini- 60 tial tension than is necessary, after which one or more of the bends are partially straightened to take out a part of the tension and leave just the amount necessary to give 65 the arms sufficient resiliency and holding ability.

In the form shown, one of the arms 2 of the clasp is longer than the other, say ap- 70 proximately an inch longer, and the end of 65 the shorter arm is flared outwardly, as at 5, to form a mouth 6 adapted to readily receive the edges of the sheets of paper or the like to be inserted in the clasp.

An aperture 7 may be provided in one side 70 of the eye 1 or in the inner end portion of one of the arms 2, so that if desired, the clasp can be readily suspended in vertical position.

The clasp so far described is identical 75 with the one described and claimed in my co-pending application before referred to. In the present improved clasp, one or both of the clasping arms 2 is so formed as to provide a space 8 between the two arms ad- 80 jacent to and back of the mouth 6. In the present illustration, this space is pro- 85 vided by depressing the metal of the shorter arm at the rear or inner end of the flared end portion 5, as clearly indicated at 9, Fig. 3, which, purely for purpose of illustration, shows the clasp arms separated by a small block 10. When the block 10, Fig. 3, is re- 90 moved, the clasp arms assume the position shown in Fig. 2, the inherent tension in the 90 shorter arm causing the metal thereof ad- 95 jacent said depression to arch or curve away from the other arm and thereby provide the space 8. This space enables paper sheets or the like, after having passed through the 95 mouth of the clasp and between the pinch- 100 ing contacting portions 9 and 11 of the arms at the inner end of the mouth, to be readily and easily moved or guided between the arms to the inner contacting portions 12, 13 of the 100 arms, which, with contacting portions 9, 11, 105 securely and firmly bind together the papers or the like and hold them in proper position in the clasp. By the provision of this space adjacent the mouth of the clasp, buckling 105 and shifting of the paper sheets, etc., while inserting them into the clasp, are avoided, thereby materially increasing the efficiency 110 of the clasp. Moreover, the depressed portion 9 engages the other arm with increased

pressure, which effectively assists in preventing shifting of the paper sheets or the like in the clasp.

Having described my invention, I claim:

5. 1. A clasp having two spring metal arm portions contacting at separated regions one intermediate their ends and another near the outer free end of one of said arm portions, said arm portions being so formed as to provide between said separated contacting regions and adjacent the outer one thereof and remote from the other a region where the arm portions do not contact, whereby articles passed between the outer contacting 10 arm portions may be readily moved between the non-contacting arm portions to the inner contacting arm portions.

15. 2. A clasp having two spring metal arm portions contacting intermediate their ends, one of said arm portions being provided near its outer end with a depressed portion whereby the two arm portions contact at this

point, said depressed portion being so formed as to provide between said contacting arm portions and adjacent the outer one thereof 25 a space between said arm portions, whereby articles passed between the outer contacting portions may be readily moved to the inner contacting arm portions.

30. 3. A clasp having two spring metal arms contacting intermediate their ends, one of said arms being provided between its said contacting portion and its free end and at a point remote from the former with a projection extending into contact with the other 35 clasp arm, said projection providing a region between said projection and said intermediate contacting arm portions and adjacent said projection where the clasp arms do not contact.

40. In testimony whereof I hereby affix my signature.

ANTHONY FRICKER.
